GLOVE DRYER

Percy Goldman, 411 E. 57th St., New York, N.Y.

Filed Oct. 2, 1961, Ser. No. 66,931

Term of patent 14 years

(Cl. D49—1)

FIG. 1

FIG. 2

FIG. 3

FIG. 4

FIG. 1 is a front elevational view of a glove dryer embodying my new design;

FIG. 2 is a rear elevational view thereof;

FIG. 3 is a side elevational view, looking from the left of FIG. 1; and

FIG. 4 is a sectional view thereof taken on the line of 4—4 of FIG. 1.

I claim:

The ornamental design for a glove dryer, as shown.
